Primary Examiner—Philip S. Hyder*Assistant Examiner*—Cynthia Underwood(74) *Attorney, Agent, or Firm*—Ryan, Kromholz & Manion, S.C.(57) **CLAIM**

The ornamental design for a coffee cup, as shown and described.

DESCRIPTION

FIG. 1 is a perspective view of my invention;

FIG. 2 is a front elevation view;

FIG. 3 is a rear elevation view;

FIG. 4 is a top plan view;

FIG. 5 is a bottom plan view;

FIG. 6 is a left side elevation view;

FIG. 7 is a right side elevation view;

FIG. 8 is a sectional view taken through line 8—8 in FIG. 4; and,

FIG. 9 is a sectional view taken through line 9—9 in FIG. 5.
